(57) **CLAIM**

The ornamental design for a sensory toy, as shown and described.

DESCRIPTION

FIG. 1 is a top, left perspective view of a sensory toy shown attached to the center of a supporting structure;

FIG. 2 is a top, left perspective view of a sensory toy;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines in the drawings depict portions of the sensory toy and form no part of the claimed design. The broken lines showing a supporting structure in FIG. 1 are for the purpose of illustrating environmental subject matter and form no part of the claimed design.

1 Claim, 8 Drawing Sheets
